UNITED STATES PATENT OFFICE.

ERNST SCHREYER, OF HAMBURG, ASSIGNOR TO WILHELM SPAETHE, OF GERA, GERMANY.

ACCORDION.

SPECIFICATION forming part of Letters Patent No. 291,782, dated January 8, 1884.

Application filed November 26, 1883. (No model.) Patented in Germany March 10, 1883, No. 10,660.

To all whom it may concern:

Be it known that I, ERNST SCHREYER, of Hamburg, Germany, have invented certain new and useful Improvements in Accordions, 5 (which have been patented by the Government of Germany by Letters Patent No. 10,660, dated March 10, 1883,) of which the following is a specification.

Accordions were heretofore locked by means 10 of exterior hooks, arranged at opposite sides of the instrument, which hooks were pivoted to one end of the instrument and applied to fixed pins at the other end. These locking-hooks frequently get loose or broken and be- 15 come perfectly useless, imparting, furthermore, an unsightly appearance to the instrument.

The object of this invention is to provide an 20 accordion with an improved locking device, that is arranged at the interior of the instrument and applied to or released from the ends of the instrument outside of the same; and the invention consists of an accordion 25 which is provided at its interior with a locking-hook, that is fulcrumed to a fixed transverse rod of the bottom case, and connected with a push or pull button passing through the wall of the bottom case, so that the locking-hook is released from a fixed transverse 30 rod of the top case, or applied thereto, according as the accordion is to be opened or closed after use.

In the accompanying drawings, Figure 1 represents a vertical longitudinal section, and Fig. 2 35 a vertical transverse section, of an accordion furnished with my improved locking device.

Similar letters of reference indicate corresponding parts.

In the drawings, A represents the bottom, 40 and B the top case or end, of the accordion; C, the bellows; D, the strapped handle of the bottom case, and D' the strapped handle of the top case. The locking device is arranged at the interior of the accordion, and consists 45 of a hook which is fulcrumed to a fixed rod, w, that extends transversely from one end wall of the bottom case to the other end wall of the same, and of a second fixed rod, h, that extends transversely from one end wall to the 50 other, of the top case. If the top and bottom cases and the bellows of the instrument are

sufficiently pressed together, the hook R engages the fixed rod h, and holds thereby the parts of the instrument securely together. At its pivoted end the hook R is provided with 55 a bent arm or eye, r, which passes through an eye at the inner end of the shank p of a push-button, o, which latter passes through an opening in the handle D of the bottom case, A. The shank p is guided in a hole of the wall of 60 the bottom case, and provided with a collar, i, against which presses the free end of a hand-spring, f, which is attached at its opposite end to the inner side of the wall of the bottom case. The spring f serves to keep the push-button o 65 in position until depressed, and retains the locking-hook in position on the fixed transverse rod h.

In order to open the instrument, the accord- 70 ion is taken hold of at the handles D D' and pressed together, so as to facilitate the disengaging of the locking-hook R from the rod h. Simultaneously the push-button o is depressed and the hook R swung back away from the rod h, as shown in dotted lines in Fig. 1. The 75 bellows can now be expanded, and the instru- 80 ment is ready for use. By the expansion of the bellows the ends of the instrument are far enough apart so that the locking-hook cannot engage the wire h. To accomplish this it is necessary to compress the bellows by the top 85 and bottom cases sufficiently, so that the locking-hook R can engage the rod h, while the push-button is simultaneously depressed for a moment, so as to move the hook sidewise out of the way of the rod h and facilitate there- 90 by the locking operation. In the locked po- 95 sition of the instrument the bellows are com- pressed, and exert thereby a pressure on the locking device, so that the instrument cannot be opened, even by an accidental depression of the push-button.

In place of the spring-pressed push-button, the locking-hook R may be operated by a draw-rod, Z, which is connected directly to 95 the shank of the hook R, passed through a hole in the side wall of the bottom case, A, and provided at the outer end with a button, K. To operate this arrangement the button K is simply pulled after the bellows is compressed, 100 and thereby the locking-hook released from or applied to the rod h.

Having thus described my invention, I claim as new and desire to secure by Letters Patent—

1. In an accordion, the combination of the ends and intermediate bellows with an interior locking device adapted to connect the ends, and means whereby the locking device is applied to or released from the ends from the outside of the instrument, substantially as set forth.
- 10 2. The combination of a bottom case having a fixed transverse rod, an intermediate bellows, a top case having a fixed transverse rod,

a locking-hook applied to the transverse rod of the bottom case, and means whereby the locking-hook can be applied to or released from the rod of the top case from the outside of the instrument, substantially as specified.

In testimony that I claim the foregoing as my invention I have signed my name in presence of two subscribing witnesses.

ERNST SCHREYER.
